HYPEREXTENSION FRAME

Claude H. Ford, Birmingham, Ala., assignor to
Harry H. Leiter, Warsaw, Ind.

Application July 22, 1938, Serial No. 220,653

6 Claims. (Cl. 128—84)

My invention relates to improvements in the structure of hyperextension frames for surgical treatment of spinal injuries.

It is an object of my invention to provide an improved hyperextension frame that is adjustable to establish proper pressure at a position along the spine which holds the vertebrae in their natural relative positions without impingement of the spinal cord.

Another object of my invention is to provide a hyperextension frame having a body support web and means for adjusting the tension of the web to provide variations in the web surface from a taut comparatively hard surface to a substantially hammock-like surface, in accordance with the desires of the surgeon.

Another object of my invention is to provide a hyperextension frame so constructed and arranged that bed pan service is easily rendered without disturbing the patient.

Other objects will be apparent from the following description, reference being had to the accompanying drawings in which a preferred embodiment of my invention is clearly shown and described.

25 In the drawings:

Fig. 1 is a perspective view of a preferred embodiment of my invention;

Fig. 2 is a perspective view of a frame structure utilized in the preferred form of my invention;

Fig. 3 is a sectional view taken substantially on the line 3—3 of Fig. 2 and in the direction of the arrows; and

Fig. 4 is a sectional view taken in the direction of the arrows and substantially on the line 4—4 of Fig. 1.

With particular reference to the drawings, a base 10 has sides 11 and 12, a foot end 13, and a head end 14. The sides 11 and 12 and the ends 13 and 14 are preferably made of angle strips rigidly secured together in rectangular form by welding, or other suitable means. A shaft 15, having threaded ends 16 and 17, extends through openings in the sides 11 and 12 near the foot end 13 of the base and provides a fulcrum support for the ends of a pair of resilient strips 18 and 19. The strips 18 and 19 are so proportioned in breadth and thickness that although they are resilient and can be flexed in one direction, they are practically rigid with respect to forces tending to flex them in directions transverse to the normal flexure. The fulcrumed ends of the strips 18 and 19 are preferably bent around end portions of a spacer sleeve 20 and clamped therearound by a rivet 21, or other suitable means. The spacer sleeve 20 is mounted on the shaft intermediate the sides 11 and 12 of the frame 10. Nuts 22 and 23, threaded onto the ends 16 and 17 of the shaft 15, and co-operating washers 24

and 25 hold the shaft 15 in position with respect to the frame 10.

The resilient strips 18 and 19 extend substantially parallel to each other and have their extending ends rotatably connected to a spacer sleeve 26 by having those ends bent around end portions 27 and 28 of the spacer sleeve 26, which end portions 27 and 28 are preferably smaller in diameter than the rest of the sleeve 26. The strips 18 and 19 are secured around the end portions 27 and 28 of the spacer sleeve 26 by rivets 29, or other suitable means. A shaft 30 extends through the spacer sleeve 26 and has nuts 31 and 32 threaded onto the ends thereof, which, together with co-operating washers 33 and 34, hold the shaft 30 in place and hold the end of the strips 18 and 19 on the end portions 27 and 28 of the spacer sleeve 26. Substantially parallel bolts 35 and 36 comprise a link and each have one end secured to the spacer sleeve 26. The bolts 35 and 36 extend outwardly from the spacer sleeve 26 and are substantially perpendicular to the axes of the shaft 20 and spacer sleeve 26. The bolts 35 and 36 extend through sleeves 37 and 38, respectively, that are rotatably secured to the sides 11 and 12 of the base 10 near the head end 14 thereof by studs 39 and 40. The studs 39 and 40 are mounted in bearing blocks 41 and 42 that are secured to the sides 11 and 12, respectively, and have threaded ends 43 and 44 that extend through the sides 11 and 12. Nuts 45 and 46, threaded onto the ends 43 and 44 of the studs and co-operating washers 47 and 48 hold the studs 39 and 40 in position with respect to the sides 11 and 12 of the frame. The sleeves 37 and 38 preferably comprise split bearings having the halves thereof bolted together as at 49. Flanged hand nuts 50 and 51 are threaded onto the bolts 35 and 36 and are rotatably supported by the sleeves 37 and 38, respectively, so that manual operation of the hand nuts 50 and 51 adjusts the distance between the sleeve 26 and the head end 14 of the frame. This moves the head ends of the strips 18 and 19 toward or away from the head end 14 of the base, depending upon the direction of the rotation of the hand nuts 50 and 51.

Screw jacks 52 and 53 are secured to brackets 54 and 55, which are, in turn, removably secured to the sides 11 and 12 of the base by bolts such as 56, or other suitable means, which are easily removable. The jacks 52 and 53 support the midportions of the strips 18 and 19, respectively. The bolts, such as 56, which secure the brackets 54 and 55 to the sides 11 and 12, are adapted to be mounted in various pairs of spaced holes, such as 57 and 58, along the sides 11 and 12, respectively, to accomplish movement of the position of the jacks 52 and 53 longitudinally of the sides 11 and 12. The position of the jacks 52 and 53, 60

- with respect to the sides 11 and 12, controls the place of the maximum curvature of, or intermediate support for, the strips 18 and 19, in accordance with the requirements of the case.
- 5 The jacks 52 and 53 have base portions 59, screws 60 that extend into openings in the base portions and have integral heads 61, and manually operable adjusting nuts 62 that are threaded onto the screws 60 and supported by the base portions 59. The heads 61 preferably have integral flanges 63 adjacent the inner surfaces of the strips 18 and 19 to prevent turning of the screws 60, with respect to the base portions 59, and provide support for inward stresses on the strips 18 and 19. Adjustment of the jacks 52 and 53 by manual operation of the adjusting nuts 62 changes the curvature of the strips 18 and 19.
- A web 64, comprising a sheet of canvas, or other suitable material, has edge portions 65 and 66 doubled under and sewed, as at 67 and 68 to provide hems through which the strips 18 and 19 extend to stretch the web and thereby provide a support for a patient, which has a curvature determined by the curvature of the strips 18 and 19. A portion 69 of the web is also doubled under and sewed, as at 70, to provide a hem through which the sleeve 20 extends to support the web at the foot end 13 of the frame. Eyelets, such as 71, are provided in the web along the head end thereof. A lace 72, extending through the eyelets 71 and around the spacer sleeve 26 is utilized for adjustably supporting the web at the head end of the frame. By pulling the lace 72 taut, the web is pulled taut to provide a comparatively hard surface. By loosening the lace 72, the web is loosened to provide a more hammock-like surface, the adjustment of the web being selected by the surgeon.
- 40 An opening 73 is provided in the web 64 substantially midway between the strips 18 and 19 and nearer to the foot end of the web than to the head end thereof to facilitate the rendering of bed pan service without disturbing the patient. 45 The opening is preferably narrow so as to minimize any tendency or possibility of bed sores or irritation resulting to the patient from the edges of the opening. The opening 73 is provided with a cover 74 that is preferably sewed to the web 50 along one edge of the opening, as at 75, and that is normally held in position over the opening by snaps, such as 76, or other suitable means. By disengaging the snaps 76, the cover 74 drops down out of the way, as indicated by the dotted 55 lines at 74a in Fig. 4. The opening 73 is preferably long enough to accommodate different sizes of patients and somewhat different longitudinal placement of different patients on the web 64.
- From the foregoing description it is apparent 60 that a sturdy hyperextension frame is provided that is not only adjustable to vary the curvature of the frame surface, but is also adjustable to vary the position or place of maximum curvature 65 and to vary the tautness or hardness of the body support web to suit particular cases. Beside these features, a narrow opening is provided for bed pan service, which opening is made narrow so that the weight of the patient is almost entirely supported by the surface of the web without sufficient pressure against the edges of the opening to cause bed sores or irritation at those edges.
- While I have illustrated and described a preferred embodiment of my invention, many modifications may be made without departing from

the spirit of the invention and I do not wish to be limited to the precise details set forth but desire to avail myself of all changes within the scope of the appended claims.

I claim:

1. A hyperextension frame comprising, in combination, a base, a pair of substantially parallel resilient strips each having one end hinged to the base and having their other ends secured together, means for adjusting the said other ends toward and away from the base, screw jacks for supporting the strip intermediate the ends thereof, said jacks being supported by the base and adjustable longitudinally of the strips, and a web secured to the strips and supported thereby to provide a body support.

2. A hyperextension frame comprising, in combination, a base, a pair of substantially parallel resilient strips each having one end hinged to the base and having their other ends secured together, means for adjusting the said other ends toward and away from the base, screw jacks for supporting the strips intermediate the ends thereof, said jacks being supported by the base and adjustable longitudinally of the strips, and a web secured to the strips and supported thereby to provide a body support, said web having an opening therein intermediate the resilient strips.

3. A hyperextension frame comprising, in combination, a base, a pair of separated and substantially parallel resilient strips extending longitudinally of the base and having their ends hingedly connected to the base, longitudinally and vertically adjustable supports for the strips intermediate the ends thereof, a web stretched between the resilient strips to provide a body support, and lacing at one end of the web for controlling the tension of the web.

4. A hyperextension frame comprising, in combination, a base comprehending sides, a head end and a foot end; substantially parallel resilient strips extending longitudinally of the sides of the base, said strips being separated by a spacer and hingedly secured to the base at the foot end thereof; a pair of screw jacks, each of which is mounted on one of the sides of the base and adjustable longitudinally thereof, said jacks supporting the strips intermediate the ends thereof; a pair of bolts connected to the strips near the head end of the base and providing means for controlling the distance between the strips and the head end of the base; and a web secured to the strips.

5. In a hyperextension frame, the combination comprising, a frame comprehending a pair of substantially parallel resilient side strips and a pair of substantially rigid ends, a web stretched over the frame, said web having a longitudinal elongated opening therein intermediate the resilient sides and nearer to one end than the other, and a flap and co-operating fastening means for covering the opening.

6. In a hyperextension frame, the combination comprising, a base, a resilient strip having one end hinged to the base and having a link comprising a screw hinged to the other end, an adjustable support mounted on the base and adapted to be moved longitudinally of the strip intermediate the ends thereof, and means cooperating with said screw and adjustably securing the link to the base for varying the vertical distance between said other end and the base.
